Primary Examiner — Susan Bennett Hattan*Assistant Examiner* — Lauren D McVey(74) Attorney, Agent, or Firm — Philip H. Burrus, IV(57) CLAIM

The ornamental design for a medical gown, as shown and described.

DESCRIPTION

FIG. 1 is a front elevation view of a medical gown illustrating my new design; and,

FIG. 2 is a rear elevation view thereof.

The long dash broken line between the neck and opening along the back of the gown is a perforation and forms part of the claimed design. The evenly spaced broken lines are directed to environment and form no part of the claimed design. The dot-dash broken lines represent the bounds of the claimed design and form no part of the claimed design. The design consists of the appearance and shape of a medical gown in a flat plane with no depth or contour.
